UNITED STATES PATENT OFFICE.

THOMAS H. MENCHION, OF FALL RIVER, MASSACHUSETTS.

SEATING ARRANGEMENT FOR CARS.

1,148,917.

Specification of Letters Patent.

Patented Aug. 3, 1915.

Application filed April 6, 1915. Serial No. 19,473.

To all whom it may concern:

Be it known that I, THOMAS H. MENCHION, a citizen of the United States, residing at Fall River, in the county of Bristol and 5 State of Massachusetts, have invented certain new and useful Improvements in Seating Arrangements for Cars, of which the following is a specification.

This invention relates to passenger street 10 cars and more particularly to the seating arrangement therefor with especial regard to the central side entrance type of car provided in each end with a motorman's cab, the objects being to obtain a large seating 15 capacity without interfering with the comfort of the passengers and to this end my invention consists in the arrangement of seats as hereinafter set forth, illustrated and claimed.

20 In the accompanying drawings: Figure 1 represents a longitudinal horizontal section through the upper part of a car, showing a top plan view of seats arranged according to my invention; several of the seats 25 being illustrated in folded position; Fig. 2, a vertical cross section on line 2—2 of Fig. 1, looking in the direction of the arrows; and Fig. 3, a side elevation of one of the 30 chairs or seats used, being of the individually automatically folding type.

Referring now in detail to the drawings; A designates the car floor divided by the sunken lateral central platform *a*, B the 35 sides of the body of the car, C the ends, D the motorman's cab at each end provided with a door E, the walls and door of these 40 cabs being provided with glass panes so that the motorman may see clearly to the rear and avoid accidents to passengers when getting on or off the car.

F indicates the central side entry and exit doors, G the steps as usual, H hinged stair well guards to cover the stair wells when not in use and I indicates hand rails attached to 45 the underside of the guards H and brought into operative position by the turning up of the guards H into the position indicated in dotted lines in Fig. 2.

All parts above referred to are old and 50 well known, so need not be described in greater detail.

The cabs D are located on opposite sides and at opposite ends of the car. Two long 55 rows 1 of automatically folding seats extend on opposite sides of the car and opposite sides of the platform *a* from the wells

of the steps G to the ends C of the car, and similarly arranged, but reversed in position, are the rows 2 extending from the stair wells to the rear of the cabs D respectively. 60 Facing in opposite directions, abutting in each instance with one end against the adjacent cab D and stopping short of the platform *a* to leave a passage way 3 for passengers, are two rows of seats 4 on opposite sides of the longitudinal central line of the car. The passage way 3 is of sufficient width to allow passengers to comfortably pass therewith to the aisle 6 between each row of seats 4 and the adjacent row 2 of 65 seats. Aisles 7 give ready access to rows 1 and rows 4 directly from the platform *a*. A short row 5 of seats is provided on the side of each cab D facing away therefrom toward the side of the car. Aisles 7 are 70 greater in width than aisles 6 and will allow excess passengers standing room, but it is my object by the above arrangement to provide sufficient seating capacity so that with 75 cars run on a reasonable schedule it will not be necessary for any passengers to stand. 80

Any usual form of automatically individually folding chair may be used, the form shown in Fig. 3 being preferred by me. In this form the seat J is pivotally 85 mounted in the uprights K and provided with a weight L on the rear of its underface, so that the seat M will move in the direction of the arrows on being vacated by a passenger, thus giving more space. However, this form of chair is only one of many 90 that might be used and I do not wish to be considered as in any manner limited thereto or to any folding type of chair or to any other specific type of chair. 95

Having thus described my invention, what I claim as new and desire to secure by Letters Patent is:

1. In a seating arrangement for central side entrance passenger cars provided with 100 a sunken central platform, two rows of seats arranged respectively on opposite sides of said platform longitudinally of said car on opposite sides of the central longitudinal line thereof at an interval from the side 105 walls of said car and facing in opposite directions away from the adjacent wall of the car.

2. In a seating arrangement for central side entrance passenger cars provided with 110 a sunken central platform, two rows of seats arranged longitudinally of said car respec-

tively on opposite sides of said platform at an interval from the side walls of said car and facing in opposite directions.

3. In a seating arrangement for central side entrance passenger cars, two rows of seats on each side of said entrance and on each side of said car and two rows of seats, one on each side of said entrance and the central longitudinal line of the car facing 10 in opposite directions, said latter rows leaving a passageway at their inner ends for access to the side row to their rear.

4. In a seating arrangement for central side entrance passenger cars provided with 15 a sunken central platform, two rows of seats arranged respectively on opposite sides of the car and said platform and extending therefrom to the end of the car, two rows of seats similarly arranged, but 20 reversely located and stopping short of the end of the car in each instance, and two further rows of seats facing in opposite directions, arranged respectively on opposite sides of the car and on opposite sides of 25 the platform, leaving a floor space between the end of each of the last mentioned rows and the platform for easy access to the adjacent rows of seats.

5. In a street passenger car of the central side entrance type provided with a sunken lateral central platform and motorman's 30

cabs located respectively in opposite ends of the car and on opposite sides thereof, a row of seats located against the side of the car and extending from platform to the end of the car, a similar row of seats located on the opposite side of the car on the opposite side of the platform, a row of seats located against the side of the car and extending from the stair well to the rear wall of the 35 adjacent cab, a similar row of seats similarly arranged on the opposite side of the car and the opposite side of said platform, a row of seats arranged slightly to one side of the central longitudinal line of the car, 40 abutting against the adjacent cab and leaving a passageway between its inner end and the platform, a similar row similarly arranged but facing in the opposite direction 45 on the opposite side of the platform and of the central longitudinal line, and a row of seats arranged against the side of each cab and facing away therefrom substantially as 50 set forth.

In testimony whereof, I have signed my 55 name to this specification in the presence of two subscribing witnesses.

THOMAS H. MENCHION.
